(57) **CLAIM**

I claim the ornamental design for a hose, as shown and described.

DESCRIPTION

FIG. 1 is a top plan view of a first embodiment of a hose, showing my new design;

FIG. 2 is a front elevational view of the embodiment of FIG. 1;

FIG. 3 is a bottom plan view of the embodiment of FIG. 1;

FIG. 4 is a rear elevational view of the embodiment of FIG. 1;

FIG. 5 is a left side elevational view of the embodiment of FIG. 1;

FIG. 6 is a right side elevational view of the embodiment of FIG. 1;

FIG. 7 is a perspective view of the embodiment of FIG. 1; and,

FIG. 8 is an enlarged view of the embodiment of FIG. 1, taken along line 8—8 of FIG. 2.

1 Claim, 2 Drawing Sheets

FIG. 1**FIG. 2****FIG. 3****FIG. 4**

FIG. 5**FIG. 6****FIG. 7****FIG. 8****FIG. 8**
